(57) **CLAIM**

The ornamental design for a multimedia device for digital multifunction devices as shown and described.

DESCRIPTION

FIG. 1 is a front view of a multimedia device for digital multifunction devices showing my new design;

FIG. 2 is a rear view of the multimedia device for digital multifunction devices;

FIG. 3 is a plan view of the multimedia device for digital multifunction devices;

FIG. 4 is a bottom view of the multimedia device for digital multifunction devices;

FIG. 5 is a right side view of the multimedia device for digital multifunction devices;

FIG. 6 is a left side view of the multimedia device for digital multifunction devices; and,

FIG. 7 is an oblique view of the multimedia device for digital multifunction devices.

The broken lines shown in the drawings illustrate portions of the multimedia device for digital multifunction devices and form no part of the claimed design.
